(57) **CLAIM**

The ornamental design for a charging bowl for a vehicle, as shown and described.

DESCRIPTION

FIG. 1 is a front left perspective view of a charging bowl for a vehicle according to the present invention.

FIG. 2 is a front right perspective view of the charging bowl for a vehicle shown in FIG. 1.

FIG. 3 is a rear right perspective view thereof.

FIG. 4 is a rear left perspective view thereof.

FIG. 5 is a front view thereof.

FIG. 6 is a rear view thereof.

FIG. 7 is a left side view thereof.

FIG. 8 is a right side view thereof.

FIG. 9 is a top view thereof; and,

FIG. 10 is a bottom view thereof.

The broken lines in the figures are included for the purpose of illustrating portions of the charging bowl for a vehicle that form no part of the claimed design.

The letters/logo/trademark forming part of the disclosure is a registered trademark of Jaguar Land Rover Limited.
